OVERHEAD TRAVELING CARRIER

Fred P. Baertschi, Rockford, Ill.

Application October 24, 1945, Serial No. 624,308

10 Claims. (Cl. 212—131)

1

This invention relates generally to overhead traveling carriers, although it is herein disclosed as applied to hay carriers, for use in unloading hay from a hay-rack and hoisting it to the loft and depositing it there at the desired place or places.

Complicated and expensive rigs have been devised heretofore for this simple operation, usually designed and intended to be driven by a stationary engine or off the power takeoff of a tractor. Obviously, such rigs required an involved system of cables with windlasses and clutches and control levers and called for a fairly high degree of skill to operate successfully, and hence the average farmer has not looked with favor on these devices and most farmers have continued to unload hay in the slow and laborious hand method—with pitchforks. Rural electrification has become so common now that the use of electric power for such work is clearly indicated. It is therefore the principal object of my invention to provide an electric motor operated hay carrier of simple, practical and economical construction.

A salient feature of the hay carrier of my invention is the mounting of a hoist drum in a carriage having gear-toothed rollers running on perforated tracks as racks, the tracks extending the full length of the loft in the peak portion of the roof, and the rollers being driven in either direction by one reversible electric motor under remote control of the operator from the floor of the loft, and the hoist drum being driven in either direction by another reversible electric motor under remote control of the operator from the same point, each motor having forward and reverse buttons for control thereof.

Another object is to provide the tracks in parallel relation suspended on inverted U-shaped hangers, the tracks being made from angle irons for economy, one flange being perforated for rack teeth and the other flange projecting upwardly at right angles for fastening to the hangers, which are also preferably made of bent angle iron pieces, one flange being secured to the track pieces and the other flange projecting upwardly for fastening suitable hanger means thereon, where that flange is not used directly to fasten to the rafters.

Still another object is to provide a substantially fully enclosed carrier unit with the two motors mounted therein in a compact arrangement, one above and the other below the same support, thus avoiding the depositing of dirt in the motors and also reducing fire hazard. The mounting of an electrical extension cord on eyelets slidable on a

wire strung in parallel relation to the tracks and arranged to be stretched out and gathered together in the back and forth movements of the carrier is also with a view to avoiding the fire hazard which would otherwise be entailed with a sliding contact or brush that would be apt to cause sparks.

The invention is illustrated in the accompanying drawing in which Fig. 1 is a view on a small scale of a hay loft showing my improved hay carrier and track structure and extension cord support therefor; Fig. 2 is a longitudinal section on a larger scale through the carriage; Fig. 3 is a cross section on the same scale through the carriage and tracks, on line 3—3 of Fig. 2, and Fig. 4 is a sectional detail on line 4—4 of Fig. 2.

The same reference numerals are applied to corresponding parts in these views.

Referring first to Fig. 1, the numeral 5 designates the hay carrier or carriage appearing in Figs. 2 to 4, with a hay-fork 6 carried on the end of the hoisting cable 7 and arranged to be tripped from the floor 8 of the loft in the usual way by a pull on the rope 9 to deposit the hay 10 at whatever place desired. The carriage 5 runs on an elevated supporting track structure 11 which extends preferably lengthwise of the loft in the peak of the roof and is suitably secured to or suspended from the rafters. The electric motors in the carriage 5, numbered 12 and 13 in Figs. 2 to 4, are supplied with electric current from a plug 14 inserted in a wall socket through a flexible extension cord 15 which is strung by means of eyelets 16 on a tight wire 17 that is stretched in the loft from end to end in parallel relation to the track structure 11. A control panel 18 is connected to the cord 15 and has suitable push buttons 19 to close normally open switches in the panel for selective operation of the motors 12 and 13 in either direction, as desired. This panel 18 may be portable or attached to the wall 20, whichever is preferred by the operator, and it is clear that the rope 9 should be long enough to reach to wherever the operator stands while running the carriage 5 so that when the carriage has been moved to the right location for dumping its load of hay, that can be done by a pull on the rope. The carriage 5 is preferably movable all the way to one end of the barn loft, and, if the operator keeps the push button 19 depressed, an automatic overload circuit breaker (not shown) opens the circuit so that no harm is done to motor 12; likewise if any overloading of motor 13 occurs in connection with the hoisting operation. The track 11 preferably extends out on a beam ex-

tending from the barn over the loft door so that the fork 6 can be lowered directly onto the hay-rack for easy pickup of hay thereon. It requires no skill to control the movements of the carriage 5 because it is only necessary to depress one button 19 for travel in one direction and another for travel in the opposite direction; likewise for up and down movement of the fork 6. Furthermore it is a simple matter to install the track and carriage in any barn loft and the invention is usable wherever the barn has been wired for electric service.

The carriage comprises a housing 21 formed by separable upper and lower sections 22 and 23. The top wall 24 of the lower section provides a support on the top thereof for motor 12 and on the bottom of the upwardly offset end portion 25 for motor 13. This makes for great compactness, as appears in Fig. 2, the worm 26 on the armature shaft 27 of motor 13 being closely beneath the wall 24 under motor 12. Bearings 28 carried by wall 24 support the worm at opposite ends so that a good meshing engagement with worm gear 29 is assured, regardless of possible slight misalignment of motor 13 relative to the worm. The same is true of worm 30 on armature shaft 31 of motor 12 which is carried in bearings 32 projecting upwardly from wall 24, worm 30 meshing with a worm gear 34. Now, worm gear 34 is carried on cross-shaft 35 mounted in bearings 36 on wall 24 and keyed to gear-toothed rollers 37 at its opposite ends. These rollers run on spaced parallel tracks 11 in which holes 38 are punched to serve as racks. The motor 12, being reversible, therefore provides for positive drive of the carriage 5 in either direction. Other rollers 39 mounted on the other end of the carriage run on the same tracks 11 and serve to support that end of the carriage.

The worm gear 29 is keyed on another cross shaft 40 mounted in bearings 41 in the side walls of the lower housing section, said shaft also having a pinion 42 keyed thereon near one end for transmitting drive to a hoisting drum 43 by meshing engagement with a gear 44 fixed on one end thereof, said drum and gear being freely rotatable with a cross shaft 45 mounted in bearings 46 in the side walls of the lower housing section. An inturned flange 47 on one side wall of the lower housing section encloses and protects the gear 44, as indicated in Fig. 3. It is clear that the symmetrical arrangement of the supporting and driving rollers 37 and 39 relative to the housing 21 makes for smooth and easy operation. The tracks 11 are far enough apart to allow easy travel of the housing therebetween, and this arrangement insures proper meshing of the gear teeth on rollers 37 in the holes 38 at all times. Any dirt collecting on the tracks 11 will have an opportunity to drop through the holes 38 or be forced through by the gear teeth so that the rollers 37 and 39 will always run smoothly thereon.

The tracks 11 being made from pieces of angle iron are not apt to get crooked and will not bend readily under load. Furthermore, the upwardly projecting flanges 47 on these members can be welded or otherwise secured easily to the flanges 48 of other angle iron yokes or hangers 49 that are bent to inverted U-shape. The outwardly projecting flanges 50 of these angle iron hangers are easily secured to rafters or may have strips 51 fastened thereto for fastening to the rafters. Obviously, the flanges 50 give the necessary rigidity to the hangers so that the tracks 11 will re-

main a predetermined distance apart as required for easy operation of the carriage 5, and the U-shape of the hangers is of advantage in providing head-room for the upper housing section 22, which, as shown in Fig. 3, is arched to snugly enclose the motor 12. Screws 52 fasten the housing sections together. Rollers 37 and 39 are mounted between the side walls of the housing 21 and the side walls of the cover 22, as appears in Figs. 3 and 4, thus reducing likelihood of hay or any litter interfering with the easy operation of these rollers.

It is believed the foregoing description conveys a good understanding of the objects and advantages of my invention. The appended claims have been drawn to cover all legitimate modifications and adaptations.

I claim:

1. In a hay handling apparatus, the combination of an overhead track, a power operable carrier running on said track, a power operable hoist drum on said carrier, a hay fork suspended on a cable wound on said drum and openable by remote control by a rope extending downwardly from the fork, two reversible electric motors on said carrier, one associated with drive means on the carrier for back and forth movement thereof on said track, and the other associated with drive means for the drum to raise and lower the fork, a supporting guide wire extending parallel to said track, a source of electric current supply, a flexible extension cord for conducting electric current to said motors on said carrier from said current source suspended on said guide wire at longitudinally spaced points by guide members movable freely along said guide wire, and a manually operable remote control switch means connected between said extension cord and said current source for remote control of said motors.
2. In a traveling carrier, the combination of an overhead track formed by a pair of closely laterally spaced parallel angle iron members having inwardly directed longitudinal flanges and upwardly directed longitudinal flanges, inverted U-shaped suspension yokes connected to said upwardly projecting flanges, a carriage comprising an elongated housing narrow enough to operate between the rails and disposed between the inwardly directed flanges and having wheels mounted on opposite sides thereof running on said last mentioned flanges, a reversible electric motor enclosed in said housing and associated with drive means connected to at least one pair of said wheels to drive the same selectively in either direction for back and forth movement of the carriage on said track, remote control means for said motor, a hoist drum rotatably mounted in said housing having a cable wound thereon for suspending a load attaching member, a reversible electric motor also enclosed in said housing and associated with drive means connected to said drum to turn the same selectively in either direction, and remote control means for said last mentioned motor.
3. In a traveling carrier, the combination of an overhead track formed by a pair of laterally spaced parallel angle iron members having inwardly directed longitudinal flanges and upwardly directed longitudinal flanges, suspension yokes connected to said upwardly projecting flanges, a carriage disposed between the inwardly directed flanges having wheels mounted on opposite sides thereof running on said last mentioned flanges, a reversible electric motor associated with drive means connected to at least one pair

of said wheels to drive the same selectively in either direction for back and forth movement of the carriage on said track, remote control means for said motor, a hoist drum rotatably mounted in said carriage having a cable wound thereon for suspending a load attaching member, a reversible electric motor associated with drive means connected to said drum to turn the same selectively in either direction, and remote control means for said last mentioned motor, at least one of the inwardly directed flanges having gear teeth holes provided therein in longitudinally spaced relation and at least one of the driven pair of wheels having radially projecting gear teeth arranged to mesh in said holes for positive driving of the carriage.

4. In a portable carrier, the combination of a housing containing a hoist drum rotatably mounted therein in the lower portion thereof, a cross-shaft mounted in said housing above said drum carrying a pinion meshing with a gear on said drum to drive the same, a worm gear on said cross-shaft, a reversible electric motor mounted in said housing on one side of and above the cross-shaft driving a worm meshing with the worm gear, another reversible electric motor mounted in said housing directly above the worm, a cross-shaft in said housing above the first mentioned cross-shaft and on the opposite side thereof from the first motor having drive wheels mounted on the opposite ends thereof outside the housing, a worm gear on said last named cross-shaft driven by a worm driven by the second motor, and another pair of wheels mounted on said housing in the vicinity of the first mentioned motor and in longitudinal alignment with the first mentioned wheels.

5. In a portable carrier, the combination of a substantially triangular-shaped housing having opposed triangular-shaped side walls and a top wall connecting the side walls, a hoist drum rotatably mounted in the lower apex portion of said triangular housing between said side walls, a cross-shaft above said drum mounted in the side walls having a pinion thereon meshing with a gear on said drum to drive the same, a worm gear on said cross-shaft, a reversible electric motor mounted on the bottom of the top wall on one side of said cross-shaft and above the same, a worm driven by said motor meshing with said worm gear, a second reversible electric motor mounted on top of said top wall, a cross-shaft mounted in the upper portion of said housing above the first cross-shaft and on the opposite side thereof from the first motor and carrying drive wheels on the opposite ends thereof outside the housing, a worm gear on said last named cross-shaft, and a worm driven by the second motor meshing with the worm gear.

6. In a hay handling apparatus, the combination of an overhead track formed by two closely spaced parallel rails, a power operable carrier running on said track, said carrier comprising an elongated housing narrow enough to operate between said rails, rollers on opposite sides of said housing at opposite ends thereof running on said rails, and a top cover member disposed over and protecting said rollers from hay and litter, a power operable hoist drum in said housing, a hay fork suspended on a cable wound on said drum and openable by remote control by a rope extending downwardly from the fork, two reversible electric motors in said housing in longitudinally spaced relationship to one another, one associated with drive means in the housing con-

nected to certain of the rollers for back and forth movement thereof on said rails, and the other associated with drive means for the drum to raise and lower the fork, and manually operable remote control means for said motors.

5. In a hay carrier, the combination of an overhead track formed by a pair of closely laterally spaced parallel angle iron members having inwardly directed longitudinal flanges and upwardly directed longitudinal flanges, inverted U-shaped suspension yokes connected to said upwardly projecting flanges, a carriage comprising an elongated housing narrow enough to operate between said track members disposed between the inwardly directed flanges and having wheels mounted on opposite sides thereof running on said last mentioned flanges, a reversible electric motor carried on said housing and associated with drive means connected to at least one pair of said wheels to drive the same selectively in either direction for back and forth movement of the carriage on said track, a top cover for said housing enclosing the upper portions of said wheels and also said motor to protect the same from hay and litter, remote control means for said motor, a hoist drum rotatably mounted in said carriage having a cable wound thereon for suspending a hay fork, a reversible electric motor enclosed in said housing and associated with drive means connected to said drum to turn the same selectively in either direction, and remote control means for said last mentioned motor.

8. In a hay carrier, the combination of an overhead track formed by a pair of laterally spaced parallel angle iron members having inwardly directed longitudinal flanges and upwardly directed longitudinal flanges, suspension yokes connected to said upwardly projecting flanges, a carriage disposed between the inwardly directed flanges having wheels mounted on opposite sides thereof running on said last mentioned flanges, a reversible electric motor on said carriage associated with drive means connected to at least one pair of said wheels to drive the same selectively in either direction for back and forth movement of the carriage on said track, a top cover for said carriage enclosing the upper portions of said wheels and also said motor to protect the same from hay and litter, remote control means for said motor, a hoist drum rotatably mounted in said carriage having a cable wound thereon for suspending a hay fork, a reversible electric motor on said carriage associated with drive means connected to said drum to turn the same selectively in either direction, and remote control means for said last mentioned motor, at least one of the inwardly directed flanges having gear teeth holes provided therein in longitudinally spaced relation and at least one of the driven pair of wheels having radially projecting gear teeth arranged to mesh in said holes for positive driving of the carriage.

9. In a portable carrier, the combination of a housing containing a hoist drum rotatably mounted therein in the lower portion thereof, a cross-shaft mounted in said housing above said drum carrying a pinion meshing with a gear on said drum to drive the same, a worm gear on said cross-shaft, a reversible electric motor mounted in said housing on one side of and above the cross-shaft driving a worm meshing with the worm gear, another reversible electric motor mounted in said housing directly above the worm, a cross-shaft in said housing above the first mentioned cross-shaft and on the opposite side

thereof from the first motor having drive wheels mounted on the opposite ends thereof outside the housing, a worm gear on said last named cross-shaft driven by a worm driven by the second motor, another pair of wheels mounted on said housing in the vicinity of the first mentioned motor and in longitudinal alignment with the first mentioned wheels, and a top cover for said housing enclosing said second motor and the upper portions of said wheels.

10. In a portable carrier, the combination of a substantially triangular-shaped housing having opposed triangular-shaped side walls and a top wall connecting the side walls, a hoist drum rotatably mounted in the lower apex portion of said triangular housing between said side walls, a cross-shaft above said drum mounted in the side walls having a pinion thereon meshing with a gear on said drum to drive the same, a worm gear on said cross-shaft, a reversible electric motor mounted on the bottom of the top wall on one side of said cross-shaft and above the same, a worm driven by said motor meshing with said worm gear, a second reversible electric motor mounted on top of said top wall, a cross-shaft mounted in the upper portion of said housing

5 above the first cross-shaft and on the opposite side thereof from the first motor and carrying drive wheels on the opposite ends thereof outside the housing, a worm gear on said last named cross-shaft, a worm driven by the second motor meshing with the worm gear, and a top cover for said housing enclosing said second motor and the upper portions of said wheels.

FRED P. BAERTSCHI.
